(57) **CLAIM**

The ornamental design for a hair comb set as shown and described.

DESCRIPTION

FIG. 1 is a front, right and top perspective view of a hair comb set showing my design.

FIG. 2 is a front, right and top perspective view of the hair cleaner of the hair comb set in FIG. 2.

FIG. 3 is a rear, left and bottom perspective view of the hair cleaner of the hair comb set in FIG. 2.

FIG. 4 is a front elevation view of the hair cleaner of FIG. 2.

FIG. 5 is a rear elevation view of the hair cleaner of FIG. 2.

FIG. 6 is a left side elevation view of the hair cleaner of FIG. 2.

FIG. 7 is a right side elevation view of the hair cleaner of FIG. 2.

FIG. 8 is a top plan view of the hair cleaner of FIG. 2.

FIG. 9 is a bottom plan view of the hair cleaner of FIG. 2.

FIG. 10 is a front, left and top perspective view of the comb of the hair comb set in FIG. 10.

FIG. 11 is a front, left and bottom perspective view of the comb of the hair comb set in FIG. 10.

FIG. 12 is a front elevation view of the comb of FIG. 10.

FIG. 13 is a rear elevation view of the comb of FIG. 10.

FIG. 14 is a left side elevation view of the comb of FIG. 10.

FIG. 15 is a right side elevation view of the comb of FIG. 10.

FIG. 16 is a top plan view of the comb of FIG. 10.

FIG. 17 is a bottom plan view of the comb of FIG. 10; and, FIG. 18 is an exploded elevation view of the comb of FIG. 1.

The broken lines depict portions of the hair comb set that form no part of the claimed design.
